[57]**CLAIM**

The ornamental design for a tool for straightening an arrow, as shown and described.

DESCRIPTION

FIG. 1 is a perspective view of a tool for straightening an arrow embodying my new design;

FIG. 2 is an enlarged fragmentary perspective of the lugs at one end of the tool viewed above and to the rear of FIG. 1;

FIG. 3 is an end elevational view looking from the right of FIG. 1;

FIG. 4 is an end elevational view looking from the left of FIG. 1;

FIG. 5 is a rear elevational view thereof;

FIG. 6 is a top plan view thereof; and,

FIG. 7 is a front elevational view thereof.

The bottom of the tool is plain and unornamented.
